UNITED STATES PATENT OFFICE

2,029,057

LUBRICANT COOLING DEVICE

Edwin A. Chambers, St. Thomas, Ontario,
Canada

Application January 7, 1935, Serial No. 752

7 Claims. (Cl. 123—196)

This invention relates to lubricant cooling devices, and its general object is to provide a device which is primarily designed for use with an internal combustion engine for cooling and retaining the oil in the crank case thereof at a low operating temperature which not only prolongs the lubricating qualities of the oil, but allows for the use of oil of light viscosity without fear of it breaking down or thinning under the action of heat, therefore the use of my device results in easy starting of the engine in cold weather and proper lubrication thereof under all running conditions.

A further object of the invention is to provide a lubricant cooling device for an internal combustion engine or the like, that is entirely automatic in its operation, easy to install, simple in construction, inexpensive to manufacture and extremely efficient in operation and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherein like characters denote like or corresponding parts throughout the several views, and in which:

Figure 1 is a longitudinal sectional view taken through the device which forms the subject matter of the present invention.

Figure 2 is a fragmentary side elevation with parts broken away and illustrating a part of the working mechanism of my device.

Figure 3 is a perspective detail view illustrating the float latch and part of the tripping means for actuating valves of my device.

Figure 4 is a perspective view illustrating the remaining parts of the tripping means.

Referring to the drawing in detail, and particularly to Figure 1, it will be noted that my device includes a plurality of vertically arranged tubes 1 that are held in group association by upper and lower plates 2 and 3 which extend laterally beyond the outermost tubes and the latter extend into openings arranged in the plates. The plates may be of any shape, it depending upon the shape of my device and while the latter is preferably oval shape, it may be cylindrical or even of rectangular formation, with the tubes arranged accordingly.

Secured to the lower plate through the instrumentality of a flange 4 and screws as shown, is a receptacle 5 in the form of a cap, with the plate 3

providing a closure for the top thereof. The receptacle acts in the capacity of a float chamber in a manner which will be presently described. Secured to the bottom wall thereof and disposed in communication with the chamber is a nipple 6 which may act as the inlet and outlet means for the device, particularly in the form as shown, but in any event the nipple 6 has secured thereto a pipe line 7 that extends to the oil reservoir within the crank case of an internal combustion engine.

Secured to and rising from the upper plate 2 is a frame which is preferably made from a single piece of metal and includes a right angle body provided with an upper horizontal portion 8 and a vertical portion 9, the latter terminating into a flange at its lower end having an opening 10 arranged centrally therein and an apertured ear to receive a screw or the like for securing the frame to the plate 2. Cooperating with the vertical portion 9 for securing the frame to the plate, are arms 11 that depend from the horizontal portion and terminate at their lower ends in apertured ears having openings therein to receive screws or the like as clearly shown in Figure 2.

The upper horizontal portion of the frame has arranged therein parallel openings, one of which receives a nipple 12 having a cap 13 secured to the upper end thereof, and this cap is provided with an opening to the atmosphere. The other opening has secured therein a nipple 14 which in turn has secured thereto one end of a pipe line 15 that extends to and is in communication with the intake manifold of the engine. The nipple 14 has a check valve 16 therein for a purpose which will be presently apparent.

The upper plate 2 has secured thereto a receptacle 17 which is similar to the receptacle 5 and likewise acts as a cap, and by that construction, it will be apparent that the receptacles 5 and 17 are in communication with each other through the instrumentality of the tubes 1 which are preferably held in association with respect to each other by fins 18, it being obvious that the fins act as cooling means and are arranged in superposed relation with respect to each other and in close proximity.

The nipples 12 and 14 extend through the top of the receptacle 17, and each of these nipples in fact provides a valve housing, in that the lower ends thereof are in the form of valve seats to receive conical valves 19 and 20 for closing the nipples as will be apparent. The valves 19 and 20 are pivotally secured to a lever 21 that is pivoted midway its ends between the arms 11, with

the result that the valves will be seated alternately in a manner and for a purpose which will be later described.

5 Suspended in the receptacle 5 through the medium of a rod 22 is a float 23. The rod 22 extends through one of the tubes 1 and has formed on or otherwise secured to its upper end a cross portion 24 that is mounted for slidable movement in guide slots 25 arranged longitudinally in wing 10 strips 26 that are formed on and extend from the vertical portion 9. The cross portion 24 has openings disposed therein adjacent to its ends for receiving cotter pins to secure the same with in the slots, as shown in Figure 2.

15 The rod 22 extends through the opening 16. Formed on one end of the cross portion 24 is a vertical arm 27 the latter having a slot 28 arranged longitudinally therein, to receive one arm of a bell crank shaped dog 29, which is pivoted 20 midway its ends to the vertical portion 9 as best shown in Figure 4, with its other arm terminating in alignment with a shoulder 30 provided in a slot 31 extending longitudinally of and centrally in the vertical portion 9.

25 The lever 21 has its inner end extending into the slot 31 and secured to this end is an arched leaf spring 32 that is bent to be provided with a flat free end and is shaped in a manner whereby the flat free end is urged toward the shouldered 30 edge of the slot 31, so that the free end is received by the shoulder at intervals during the operation of my device as shown in Figure 4 which likewise illustrates that the free end of the spring is disposed in the path of the dog 29 35 when the free end is received in the shoulder.

Secured to and rising from the plate 2 adjacent to the vertical portion 9 of the frame is an inverted U-shaped bracket 33 for the purpose of pivotally receiving between the arms thereof a lever 34 of a float 35. The lever extends into a 40 downturned free end 36 that is normally arranged in the path of a spring pressed dog 37, the latter being preferably mounted in a slot disposed in the rod 22 and pivoted therein by a pin 38 which 45 has a strand of resilient wire 39 extending therethrough. One end of this wire is wrapped about the rod 22 while its opposite end extends through an opening in the dog 37. Therefore the pin 38 is not only held associated with the rod 22 by 50 the strand 39, but the dog 37 is spring pressed.

The particular manner of pivoting the lever 21 between the arms 11 is important, and it will be noted that the lever is enlarged midway its ends and has extending through the enlarged portion 55 a sleeve 40 through which extends a pin 41, the latter having its ends journaled in the arms 11, as shown.

The lever is normally held in the position of Figure 1 through the medium of a coil spring 42 60 that has one of its ends secured to the outer end of the lever and the other end to the free end of the horizontal portion 8, with the result that the valve 20 is normally open and the valve 19 is normally closed.

65 In the use of my device, in the form as shown, it will be obvious that when the engine is put into operation, a vacuum will be created within the device which will naturally draw the lubricant from the reservoir of the engine, up into the 70 chamber 5, tubes 1, and into the receptacle or cap 17. This takes place before my device is put into action, due to the fact that the downturned free end 36 of the lever 34 contacts the dog 37. However, when the oil lifts the float 35, the end 75 36 is moved out of the path of the dog 37, which

will cause the float 23 to rise and as the float 23 is secured to the rod 22, the cross portion 24 of the rod will contact the spring 32 and therefore rock the lever 21 to seat the valve 20 and unseat the valve 19, so as to close the pipe line to the intake manifold and to open the device to the atmosphere, consequently the oil within the device will drain back to the engine. When the spring 32 is raised, the flat free end thereof is received in the shoulder 30, as shown in Figure 4, so as to hold the valves in the position set forth until all the oil is drained from the device. As the oil is returned, the float 23 will drop and this action will actuate the dog 29 which moves the free end of the spring 32 out of the shoulder, therefore 10 disposing the lever 21 to its normal position with the valves 19 and 20 arranged as shown and the other parts disposed accordingly to begin the cycle of operation just described.

While the nipple 6 has been referred to as the 20 inlet and outlet means, it may be used only as the outlet means, and in that event the inlet means will extend from the oil supply to the receptacle 17, or at any other appropriate place, as will be apparent. The device is preferably disposed in a direct line from the air currents of the fan of the engine so that as the oil passes through the tubes 1, it will be materially cooled before being returned to the crank case.

It is thought from the foregoing description 30 that the advantages and novel features of my invention will be readily apparent.

I desire it to be understood that I may make changes in the construction and in the combination and arrangement of the several parts, provided that such changes fall within the scope of the appended claims.

What I claim is:

1. A lubricant cooling device for an engine and comprising cooling means, means whereby suction is created in said device for drawing lubricant from the engine for passage through the cooling means, and means acting alternately with the second mentioned means to break the suction to allow the lubricant to drain back to the engine.

2. A lubricant cooling device for an engine and comprising lubricant receiving chambers, cooling means in communication with said chambers, means whereby suction is created in said device for drawing lubricant from the engine into the chambers and through the cooling means, and means acting alternately with the suction means to break the suction to allow the lubricant to drain back to the engine.

3. A lubricant cooling device for an engine and comprising lubricant receiving chambers, cooling means between the chambers and in communication therewith, means having connection with the engine to create a suction in said device to draw lubricant from the engine into the chambers and through the cooling means, and means acting alternately with the means to create the suction to break the latter to allow the lubricant to drain back to the engine.

4. A lubricant cooling device for an engine and comprising lubricant receiving chambers, cooling means between the chambers and including a group of tubes in communication therewith, cooling fins for the tubes, means having connection with the engine to create a suction in said device to draw lubricant from the engine into the chambers and through the tubes, and means acting alternately with the suction means to break the suction to allow the lubricant to drain back to the engine.

5. A lubricant cooling device for an engine and comprising lubricant receiving chambers, cooling means including a group of tubes disposed between the chambers and in communication therewith, cooling fins for the tubes, means having connection with the engine to create a suction in said device to draw lubricant from the engine into the chambers and through the tubes, means for introducing atmospheric air into the device, valve means for the means connected to the engine and the air introducing means respectively, and automatic means for actuating the valve means.
6. A lubricant cooling device for an engine and comprising a pair of lubricant receiving chambers, cooling tubes between the chambers and in communication therewith, means for connecting one of said chambers with the intake manifold of the engine, means for introducing atmospheric air in the last mentioned chamber, a pivoted lever, a valve for controlling the means connected to the intake manifold, a valve for controlling the means for introducing air into the chamber and said valves being pivotally connected to said lever and means for actuating

said lever for alternately disposing the valves into and out of seated positions for creating a suction in said device for drawing lubricant from the engine for passage through the cooling means and to break the suction to allow the lubricant 5 to drain back to the engine.

7. A lubricant cooling device for an engine comprising a pair of lubricant receiving chambers, cooling tubes between the chambers and in communication therewith, means having connection 10 with one of said chambers and the intake manifold of the engine, a check valve in said means, means for introducing atmospheric air in the last mentioned chamber, a lever pivoted in said chamber, a pair of valve members carried by said 15 lever for alternately controlling the connection to the intake manifold and the means for introducing air in the chamber, and float actuated means for operating said valves through the medium of the lever, whereby to alternately 20 draw lubricant from the engine for passage through the tubes and to allow the lubricant to drain back to the engine.

EDWIN A. CHAMBERS. 25
